UNITED STATES PATENT OFFICE.

LAWRENCE BRUEHL, OF BROOKLYN, NEW YORK, ASSIGNOR TO GAS REFRIGERATION CORPORATION, OF SCRANTON, PENNSYLVANIA, A CORPORATION OF DELAWARE.

EVAPORATOR FOR REFRIGERATING APPARATUS.

Application filed January 4, 1927. Serial No. 158,845.

This invention is an improvement in evaporators for refrigerating apparatus, particularly of the absorption type. In this type of refrigerating apparatus, the refrigerant gas is separated from the absorbent liquid by the action of heat and is thereafter cooled to effect the liquefaction thereof. During the heating period, it often happens that a small amount of the absorbent liquid is also evaporated and passes over to the condenser and thence to the evaporator. As this liquid is not volatile to any considerable extent at the low temperature existing in the evaporator during the absorbing period, it will remain in the evaporator. After a large number of alternate heating and absorbing periods, there may accumulate such a quantity of the absorbent liquid in the evaporator as will seriously interfere with the efficiency of the apparatus.

The main object of the present invention is to effect the automatic return of liquid from the evaporator to the absorber during each cycle of operation and to thereby maintain at all times proper operating conditions.

The present invention is an improvement in the apparatus disclosed and broadly claimed in the Otto and Jankus Patent 1,582,882 issued April 27, 1926.

As one important feature of my invention I provide a single chamber which serves both as a receiver for the liquid drained from the body of the evaporator, and as a pressure chamber in which gas expands to force the liquid to a higher level.

As another important feature of the invention, the pressure chamber is mounted inside of the evaporator so that it is not subjected to as wide or rapid fluctuations of temperature.

As a further important feature of the present invention, I provide a simplified means for conducting liquid from the bottom of the evaporator to the return or suction pipe.

In the accompanying drawings, I have illustrated diagrammatically certain embodiments of my invention.

In these drawings:

Figs. 1 and 2 are vertical sections through evaporators embodying my invention; and

Figs. 3 and 4 are details of alternative constructions of a part thereof.

In the construction shown in Fig. 1, there

is provided an evaporator 10 which may be of any suitable size, form or construction dependent upon the character of the apparatus in connection with which it is to be used and which is to be cooled thereby. I 60 have shown this evaporator as a simple cylindrical drum, but such form is not in any way essential. A conduit 11 communicates with the upper part of the evaporator, and serves for the delivery of the 65 liquefied refrigerant to the evaporator during the heating period, and for the return of gas from the evaporator during the absorbing or cooling period.

In connection with the evaporator, 70 whether of the form shown in Fig. 1, or of other form I provide a chamber 12 which is closed at the top and sides, but communicates at the bottom with a tube 13. The chamber 12 is shown as disposed within the body of 75 the evaporator. This is desirable, but in some constructions, it might be outside. The tube is shown as a well projecting through the bottom of the evaporator and closed at its lower end. This tube or well 80 13 communicates with the lowermost portion of the evaporator by means of a port 14 which is of very small size so as to permit a restricted flow therethrough.

A conduit 15 connects the lower portion of 85 the tube 13 with the conduit 11. The connection is such that during the delivery of liquid to the evaporator through the conduit 11, the liquid will flow directly into the evaporator and will not pass down the conduit 90 15. This is accomplished in the form shown in Fig. 1 by providing the conduit 15 with a bend or goose-neck 16 which enters the upper side of the conduit 11.

Preferably, the discharge end of the pipe 95 15 delivers in the direction of the return flow of gas in the conduit 11 so that this liquid is carried along the conduit both by suction and its own velocity.

It will be noted that the lower portion of 100 the evaporator communicates with the chamber 12 through the port 14 and the tube 13. It will also be noted that the chamber 12 communicates with the return conduit 11 through the conduit 13 and the conduit 15, 105 but that this passage has a larger cross-sectional area than the port 14. The port 14 is so positioned that liquid from the bottom of the evaporator may drain through the port 14 into the tube 13. This drainage 110

may be facilitated by providing a sump 17 at the bottom of the evaporator and around a portion of the tube 13 and placing the port 14 at the lower part of this sump.

- 5 The operation is substantially as follows: At the beginning of the heating period, the pressure increases in the system and approximately the same pressure will exist in the chamber 12 as in the body 10 of the evaporator. As the pressure increases any residual liquid in the bottom of the evaporator will be slowly forced through the port 13 and will rise into the chamber 12. The gas in the compartment 12 is compressed and is liquefied by reason of the increase in pressure. This compartment may become entirely filled with liquid, there being no gas space remaining.

At the end of the heating period and the beginning of the cooling period, the pressure in the evaporator will rapidly decrease. Some of the liquid in the chamber 12 will gasify and the remaining liquid in the compartment 12 will be forced out of this chamber by this gasification. It can do this through the port 14 to the lower part of the evaporator and it can also do this through the tube 13 and 15 to the return conduit 11. As the first mentioned communication is a restricted one, while the other is open, the major portion of the liquid in the liquid in the compartment 12 will be delivered through the conduit 13 and up the conduit 15 to the return pipe 11. As there is a suction in this pipe, any liquid entering it will not flow down and out through the open end of the conduit 11, but will be carried along by the gas and will be conveyed back to the absorber. This liquid which is thus returned is that which remained unevaporated at the end of the cooling period and which contains any liquid absorbent which may have collected in the evaporator. Thus during each cycle of operation a predetermined amount of liquid from the bottom of the evaporator and containing liquid absorbent, if there be any or not, will be removed from the evaporator. If any foul gas be present in the system it will not collect in the chamber 12 as the alternate filling and emptying of the chamber will act to move such foul gas therefrom.

It is desirable that the parts be so proportioned that the distance from the port 14 to the bottom of the conduit 15 is greater than is the distance from said port 14 to the liquid level in the chamber 12. Thus the weight of the column of liquid in the conduit 13 will cause liquid to rise in the conduit 15 to the point above the liquid level in the evaporator at the beginning of the evaporating or cooling period and the return flow through the conduit 15 will be facilitated.

65 In Fig. 1 the levels are shown as they are

at the beginning of the heating period. After the liquid has been returned from the compartment 12 fluctuations in the operation may cause liquid to intermittently enter the conduit 13 through the port 14 and then be forced up the pipe 15. This operation is not desired and therefore I preferably provide an enlargement 18 in the conduit 15 toward the upper part which will permit separation of liquid and gas rising in the conduit 15 and the return flow of liquid from said enlargement instead of the delivery of such liquid to the conduit 11. The entire conduit 15 is protected against direct influence of outside heat conditions so as to minimize the vaporization in this conduit.

The walls of the compartment 12 are preferably made comparatively thick and of metal so that they have a certain cold storage capacity and this compartment will not be subject to as great temperature fluctuations as is the case with the outer walls of the evaporator. If the evaporator be employed in an air chamber, the enlargement 18 is not necessary because air has a very low conductivity and heat storage capacity; but it is desirable if the evaporator is surrounded by brine. It is not essential that the sump 17 be provided, but it is desirable to employ it, as it facilitates the drainage of liquid from the evaporator to the port 14.

In Fig. 2 there is shown a very similar construction in which the tubes 15^a and 13^a are formed as parts of a single conduit and as two upstanding arms of a U connection. In other words, in Fig. 2 I have shown the two conduits which connect the chamber 12 to the gas outlet pipe as arranged side by side, whereas in Fig. 1, one is mounted inside of the other. Otherwise the two constructions are substantially the same.

Instead of connecting the conduit 15 to the gas conduit 11 by a goose-neck as shown in Figs. 1 and 2, the conduits may be arranged one inside of the other. In Fig. 3, I have shown a conduit 15^a of smaller size than the gas conduit 11^a and projecting into the open end of the latter. Liquid flowing down the conduit 11^a will go direct to the reservoir while liquid flowing up the conduit 15^a will be caught in the flow of return gas and carried back to the absorber with said gas.

In Fig. 4 another form is shown in which the conduit 11^b is closed at the end and provided with a port 19 in the upper side thereof. The conduit 15^b terminates in a nozzle 20 disposed above and directed downwardly toward the port 19. It will be noted that here also the liquid flowing to the evaporator through the conduit 11^b overflows into the evaporator through the port 19, while liquid delivered up the pipe 15^b will pass from the nozzle 20 into the port 19 and thus back to the absorber.

Having thus described my invention, what I claim is:

1. An evaporator for an absorption refrigerating system including a main evaporator vessel, a gas outlet conduit, and a compartment enclosed within said vessel whereby the compartment is protected from direct heat interchange with the medium surrounding said vessel, said compartment having restricted communication with the lower part of said vessel and open communication with said conduit.
2. An evaporator vessel for intermittently operated refrigerating apparatus of the absorption type, having a compartment enclosed within the evaporator whereby the compartment is protected from direct heat interchange with the medium surrounding said vessel, said compartment being in restricted communication with the lower part thereof, and a conduit leading from said compartment for the delivery of liquid from said compartment to the exterior of the evaporator.
3. An evaporator for refrigerating apparatus including a vessel, a chamber entirely enclosed within said vessel and having a conduit leading from the lower part thereof and provided with a restricted port communicating with the lower part of the vessel, and a conduit connected to said first mentioned conduit for the delivery of liquid from the compartment to the exterior of the evaporator.
4. An evaporator for refrigerating apparatus including a vessel, a conduit communicating with the upper portion thereof for the delivery of liquid to the vessel and the return of gas from the vessel and means within said vessel for delivering liquid from the lower part of the vessel to said conduit at a point spaced from the end of the latter.
5. An evaporator for refrigerating apparatus including a vessel, a conduit having means for delivery of liquid thereto and the withdrawal of gas therefrom, a compartment

having in the lower portion thereof restricted communication with the lower portion of the vessel, and a conduit connecting said compartment with said first mentioned conduit within the upper part of said vessel for dumping liquid directly into the latter whereby the flow of gas from the evaporator will carry such liquid therewith.

6. An evaporator for refrigerating apparatus including a vessel, a conduit for delivering liquid thereto and withdrawing gas therefrom, a second conduit for delivering liquid from the lower portion of the vessel directly to said first mentioned conduit and having an enlargement therein intermediate to the ends thereof.

7. An evaporator for refrigerating apparatus including a vessel, a conduit for delivering liquid thereto and withdrawing gas therefrom, a second conduit for delivering liquid from the lower portion of the vessel directly to said first mentioned conduit within the upper part of said vessel, and a compartment within said vessel and having its upper part closed and its lower part in open communication with the second mentioned conduit and in restricted communication with the lower part of said vessel.

8. An evaporator for refrigerating apparatus including a vessel, a conduit for delivering liquid thereto and withdrawing gas therefrom, a second conduit for delivering liquid from the lower portion of the vessel, said second mentioned conduit having its discharge end within said vessel and so located relative to the first mentioned conduit that the liquid returned from the second mentioned conduit is delivered directly to said first mentioned conduit in the direction of the effluent of the latter and away from the evaporator.

Signed at Brooklyn, in the county of Kings and State of New York, this 31st day of December A. D. 1926.

LAWRENCE BRUEHL.
